UNITED STATES PATENT OFFICE.

ROBERT R. HUGHES, JR., OF UTICA, NEW YORK, ASSIGNOR TO UNION SPECIAL MACHINE COMPANY, OF CHICAGO, ILLINOIS, A CORPORATION OF ILLINOIS.

CONCEALED STITCHED SEAM.

Application filed December 20, 1920. Serial No. 431,931.

To all whom it may concern:

Be it known that I, ROBERT R. HUGHES, Jr., a citizen of the United States, residing at Utica, in the county of Oneida, State of New York, have invented certain new and useful Improvements in Concealed Stitched Seams, of which the following is a description, reference being had to the accompanying drawing and to the figures of reference 10 marked thereon.

The invention relates to new and useful improvements in concealed stitched seams, and more particularly to a two-line seam which can be used for seaming garments.

An object of the invention is to provide 15 a seam for the above purpose wherein one edge of two fabric sections united by the improved seam is covered with a binding and the binding is secured to the fabric sections by stitches which are concealed from view at the front or face side of the garment.

In the drawings which show by way of 20 illustration one embodiment of the invention—

Figure 1 is a plan view of a portion of two fabric sections with the invention embodied therein;

Fig. 2 is a sectional view on the line 2—2 30 of Fig. 1;

Fig. 3 is a view similar to Fig. 2, but showing a slightly modified arrangement of the binding, and

Fig. 4 is a sectional view on the line 4—4 35 of Fig. 2 and showing the stitches diagrammatically.

In carrying out the invention, the two fabric sections A and B are overlapped as indicated in the drawings, and the edge portion 40 1 of the fabric section A is inturned or infolded so as to lie between the two fabric sections. A line of stitches 2 indicated diagrammatically in the drawings is passed through the fabric section B, the 45 inturned portion 1 and the body of the fabric section A adjacent to the line of fold 3 in the fabric section A. Extending about the edge 4 of the fabric section B is a binding strip 5. Said binding strip 5 has its upper or outer face portion 6 inturned or 50 infolded as indicated at 7 so as to lie between the fabric section B and the outer face portion 6 of the binding strip. There is also shown in Fig. 2, the under face portion 8 55 of the binding strip inturned as indicated

at 9. The structure shown in Fig. 3 is similar to that of Fig. 2, except that this under portion 8 of the binding strip is not in-turned but lies flat between the two fabric sections. The binding is secured to the two fabric sections, and the two fabric sections are secured together by a line of stitches 10. Said line of stitches 10 include a needle thread which lies between the inturned portion 7 and the outer face 60 portion 6 of the binding strip so that said needle thread is completely concealed by the outer face portion of the binding strip. Said needle thread is indicated at n in the drawings. The needle thread is formed into 70 a series of loops n' which pass through the inturned portion 7 of the binding strip and the fabric section A, thus securing the binding strip firmly and tightly about the edge of the fabric section B and securing both 75 the binding strip and the fabric section B to the fabric section A.

In Fig. 4 of the drawings I have shown more in detail, but yet diagrammatically, the arrangement of the stitches 10 relative 80 to the fabric sections and the binding.

It will be apparent as above noted that the needle thread n is completely concealed from the outer or face side of the garment, and that in appearance, the edge of the garment is bound with a binding without any stitches showing, and at a distance from the binding is a parallel line of stitching. This makes a very neat appearing seam for garments, and particularly useful in connection 85 with the seaming of trousers for dress suits, suits for letter carriers, bath robes, and the like.

It is obvious of course, that the stitches for uniting the parts may be of any well 90 known type. The essential feature consists in the placing of the stitches so that they will be concealed.

Having thus described the invention, what I claim as new and desire to secure by 100 Letters-Patent, is—

A concealed stitch seam comprising two overlapped fabric sections, the edge portion of one of the fabric sections being inturned, a line of stitches passing through said fabric sections adjacent the fold in said in-turned portion, a binding extending about the edge of the other section and including outer and under face portions, the outer face portion thereof being inturned, a line of 105 110

stitches for securing the binding to the edge portion of the fabric section and for securing the fabric sections together, including a needle thread lying between the inturned 5 portion of the binding strip and the outer face of said binding strip and formed into loops extending through said inturned

portion of the binding strip, the fabric section around which the binding strip is placed, the under face portion of the binding strip and the other fabric section. 10

In testimony whereof, I affix my signature.

ROBERT R. HUGHES, JR.
